INVENTOR

Dear A. Ross,

UNITED STATES PATENT OFFICE

2,062,825

METHOD FOR FORMING COMBUSTIBLE MIXTURES

Oscar A. Ross, New York, N. Y.

Continuation of application Serial No. 80,000,
January 8, 1926. This application July 22,
1931, Serial No. 552,528

5 Claims. (Cl. 261—90)

This invention refers to apparatus for producing combustible mixtures from non-readily volatilized liquid fuels and more particularly to that class of apparatus for producing said mixtures for internal combustion motors and fuel oil burners.

Internal combustion motors employing the more heavy hydro-carbon oils are known as the Diesel type and the fuel is either solidly or air injected thereinto, the heat of compression acting to destructively distill the more or less solid fuel particles injected into its cylinders. Other lower compression motors employing kerosene as fuel are provided with gasifying devices heated by the exhaust gases for converting the liquid fuel into a gas before entry into the motor cylinders thereof.

The difficulty in employing non-readily volatilized liquid fuels in low compression motors arises from the fact that a comparatively small portion of the fuel is readily volatilized at atmospheric temperature, and therefore the comparatively large fuel particles produced in ordinary carburetors do not furnish sufficient globular surface whereby the readily volatilized portions therein are exposed to form an electrically ignitable mixture when starting a motor from cold state. Furthermore assuming the mixture to be ignitable, the comparatively large particle size of the fuel prevent its being wholly consumed during the power cycle of the motor thereby causing poor economy, or in the case of an oil burner, will produce soot or mal-combustion owing to the improper balance of fuel and air required to maintain combustion. Furthermore in the case of the internal combustion motor, the comparatively large particle size of the fuel produces a comparatively slow combustion, or destructive distillation thereof thereby producing a comparatively slow power cycle and in the case of motors operating at high rotative speed the efficiency thereof will be comparatively low.

The applicant has discovered that by mechanically breaking up the non-readily volatile fuel of a combustible mixture into particle size which is comparatively small as compared to the particle size of mixtures produced by ordinary carburetors, that said mixture is not only readily ignitable in cold state, but also has an exceedingly rapid flame propagation therethrough thereby producing the rapid explosion required in high speed motors. The mechanical breaking up of the fuel is accomplished by directing a stream of non-readily volatilized fuel against moving fuel dispersion, or disintegrating members simul-

taneously with creating an air flow into which the dispersed fuel is suspended, the dispering members, by a beating and cutting action breaking up said fuel to particle size approximating the micron, the air suspended fuel particles appearing as a fog or nebular body, said particles, as in the case of aqueous fog, being gas tensionly suspended in the air, it being suggested that said particles are electro-statically separated one from another and therefore remain as closely approximated but independent bodies.

By thus reducing non-volatile liquid fuels to comparatively small particle size, a tremendous globular area of the fuel is exposed to the air in which it is suspended. Therefore a comparatively large portion of the more readily volatile components of the fuel are exposed and converted into a gas which comingled with the surrounding air produces a readily ignitable mixture throughout the entire combustible mixture, this condition occurring even at atmospheric pressure. The aforesaid readily ignitable mixture furnishes a path of substantially instantaneous flame propagation throughout the combustible mixture, and owing to the comparatively small particle size of the dispersed fuel, the flame propagation throughout the readily ignitable mixture acts to substantially instantaneously distill, or gasify said particles thereby effecting comparatively rapid flame propagation through the entire combustible mixture and therefore comparatively rapid explosion thereof whereby high speed internal combustion motors may be economically operated. The applicant's novel form of combustible mixture is equally well adapted for use in fuel burners, the highly dispersed fuel burning completely without forming soot on the burner or the furnace chamber wherein it is located.

The applicant's combustible mixture also forms an ideal mixture for starting internal combustion motors from a cold state without the abnormal addition of liquid fuel much of which may flow to the crank of the motor and dilute the lubricating oil therein.

It is one object of this invention to furnish apparatus for producing a combustible mixture having the characteristics hereintofore named and wherein the nonreadily volatilized liquid fuels are disintegrated, dispersed, nebulized, or reduced to particle size approximating the micron in diameter and all the particles are of substantially uniform size and closely approximated giving the appearance of fog.

Another object is to furnish apparatus for producing combustible mixtures from hydrocarbon

fuels wherein no comparatively small orifices or passageways are required for controlling the flow of said fuel in forming a combustible mixture, in this manner preventing failure of the apparatus due to the clogging of said orifices and passageways.

Other objects and advantages will appear as the description of the invention progresses, and the novel features thereof will be pointed out 10 in the appended claims.

This invention consists in the novel construction and arrangement of parts hereinafter described, delineated in the accompanying drawings and particularly pointed out in that portion 15 of this instrument wherein patentable novelty is claimed for the certain and peculiar system and apparatus, it being understood that, within the scope of what hereinafter thus is claimed, divers changes in the form, proportions, size and minor 20 details of the structure may be made without departing from the spirit of the invention, or sacrificing any of its details.

In describing the invention in detail, reference is had to the accompanying drawings wherein 25 I have illustrated one embodiment of the invention, and wherein like characters of reference designate corresponding parts throughout the several views, and in which:—

Fig. 1 is a sectional view on the line A—A of 30 Fig. 3 and shows various features of the construction of the combustible mixture producing means and the combustible mixture actuating means. Fig. 2 is a cross-sectional view, the right hand half of which is taken on line B—B of Fig. 35 1 and the left hand half on line C—C of Fig. 1. Fig. 3 is an end view of the apparatus in Fig. 1 the direction of the view being indicated by the line D—D in that figure. Fig. 4 is a view partly diagrammatic and partly in section of various 40 features of the mechanisms for producing and burning combustible mixtures and also includes a wiring diagram of the circuits for controlling said mechanisms. Fig. 5 is a diagrammatic view illustrating an installation in which the combustible mixture producing means and the actuating means for the mixture are placed in a 45 location remote from the burner arranged to consume said mixture.

Referring to Figs. 1, 2 and 3, the combustible 50 mixture producing and actuating unit 2, comprises motor 3, blower or fan 4, and fuel dispersing or nebulizing unit 5, suitably mounted on a base as 6. Motor 3, comprises frame 7, armature 8, having shaft 9, mounted in bearing 55 10, and attached to the driving end of which is secured hub 11, supporting blades 12—12, rotating in housing 13 having annular side walls 14 and 15 and, also exhaust opening 16.

Nebulizing unit 5 comprises housing 17, one 60 end of which is joined to housing 13 by conical deflector 18, the other end supporting bearing bracket 19, bolts 20 and nuts 21 serving to adjustably unite said housing and bracket together 65 with the fixed nebulizing member 22.

Secured to bearing bracket 19, by bolts 23 and nuts 24, is pump body 25 having gland nut 26 adapted to pack shaft 27 against leakage from pressure produced by pump gears 28 and 70 29, gear 28 being keyed to shaft 27 and gear 29 rotating on its own shaft. Also secured by bolts 23 and nuts 24, is the bearing housing 30 supporting ball bearing 31, the inner race of which is secured to shaft 27 by nut 32, cap 33 acting 75 to enclose said bearing.

Also secured to bearing bracket 19, is fitting 34 adapted to receive nozzle 35.

Fixed nebulizing member 22 comprises upper and lower distribution plates or members 36 and 37, also nebulizing vanes or disintegrators 38—38. 5 Fixed nebulizing member 39 secured to housing 17 by brackets 39a—39a, supports nebulizing vanes or disintegrators 40—40.

Shaft 27, the driven end of which is keyed to hub 11, supports rotating spider nebulizing member 41 comprising hub 42 keyed to shaft 27, bolts 43—43 and plate 44 securing spider plate member 45 thereto, said member supporting nebulizing or disintegrating vanes 46 and 47.

Annular members 48 having openings 49 serve 15 to prevent liquid fuel from being drawn into the blower housing 13.

Reserve fuel reservoir 50, secured to housing 17 by brackets 51—51, has over-flow pipe 52, inlet 53, outlet 54, and heater unit 55 insulatively 20 supported thereon.

Orifice 56 serves to drain the non-nebulized liquid fuel from housing 17 to main reservoir 92.

Referring to Fig. 4, illustrating a complete combustible producing and actuating unit together with a fuel burner and system of control therefor, the combustible mixture producing and actuating unit 2 is connected to burner 60 by pipe 61.

Burner 60 comprises main burner member 62, 30 circular in form and having threaded extension 63 receiving nut 64 arranged to secure cylindrical insulating member 65 supporting electrode 67 positioned by nuts 66—66, said electrode receiving energy through terminal 67a. Loosely 35 mounted on the upper end of said electrode is vaporizing plate or member 68 having vaporizing ribs 69—69 radially disposed. Orifice 70 serves to drain any liquid entering chamber 71. Pipe 72 drains off any liquid which may flow to chamber 73. Electrodes 74—74 serve to form an air gap between electrode 67 and ribs 69—69 across which the ignition spark jumps for initially igniting the combustible mixture supplied to the burner by the unit 2.

Thermoresponsive device comprises housing 76 and annular members 77 and 78 clamped between which are thermoresponsive disk 79 and heat radiating disk 80. Thermoresponsive disk 79 composed of bi-metallic material is arranged to have the center portion thereof abruptly assume either one of two stable positions, and during the movement thereof is arranged to move operating rod 81 rigidly secured thereto, said rod being arranged to actuate contact lever 82 pivoted at 83.

Dash-pot 84 having piston 90 secured to armature 85 of solenoid 86 by rod 92a, comprises cylinder 87 having valve 88 arranged to permit piston 90 to lower rapidly but rise slowly. Orifice 89 permits a quick rising of said piston during the initial upward movement thereof only, the orifice 91 thereafter restraining a slow movement thereof.

The operation of the system is as follows; 65 referring to Fig. 4 all the parts are shown in inoperative position, it being assumed that the temperature of space 100 is sufficiently high to maintain thermostat 101 in open position. Upon a predetermined lowering of the temperature in 70 said space said thermostat will act to establish the following circuit; from positive energy to contact 102, wire 103, operating winding of solenoid 86, wires 104, 105, 139, circuit closer 132, wires 140 and 141 to negative energy. With said 75

circuit energized armature 85 moves up quickly until piston 90 covers port 89, said movement causing circuit closer 106 to establish the following circuit; from positive energy to contact 5 lever 82, wires 107, 162, circuit closer 163, wire 108, where it divides, the fuel heating circuit running through wire 109 to heating unit 55 and thence to negative energy, the other branch, namely the ignition circuit, running through wire 10 110, transformer 111, wire 112, circuit closer 106 and wire 113 to negative energy. This latter circuit, by induction in transformer, produces high voltage current through wires 129 and 130 acting to create ignition sparks between electrodes 15 67 and 74—74.

After a predetermined interval of time, the upward movement of armature 85 will actuate circuit closer 114 to establish the motor operating circuit as follows; from positive energy to 20 wire 115, wires 117 and 118, circuit closer 114, wires 119 and 133, to motor 3 and thence to negative energy by wire 120. This circuit acts to operate motor 3 and rotation of shaft 27 will cause pump 30 to withdraw fuel from main reservoir 25 voir 92 through pipe 93, strainer 94, pipe 95, check valve 96, pipe 97, said pump delivering said fuel to the reserve reservoir 50, said fuel eventually flowing through pipe 99 to nozzle 35, the surplus fuel returning to main reservoir 92 30 through pipes 52 and 121.

After being heated by heater 55 the fuel first flows to nozzle 35 and thence to distributor plate 36 where it is divided into a number of streams by grooves or troughs 122—122, thereafter falling 35 to distributor plate 37 and is further sub-divided into a larger number of streams by grooves or troughs 123—123, thereafter passing to the rapidly revolving nebulizing members 46—46 where the first stages of substantial dispersion or 40 nebulizing begins, thereafter passing through stationary nebulizing members 39 and 38 to moving nebulizing members 47—47 for further nebulization thereby. It will be noted that the angularity of said moving and stationary members is such that not only will it effect outward movement of the nebulized and non-nebulized fuel but will also create an outwardly moving air current through said members, said air entering 45 through openings 125—125 in member 19, thence passing through openings 159 and 160 in member 22, thence through said nebulizing members and 50 therein receiving the dispersed fuel for forming the combustible mixture whereafter said mixture passes to chamber 124 around the outer 55 edge of member 39 as shown by the several arrows. Any fuel not nebulized during its movement through said nebulizing members is returned to the main reservoir through passageway 56, said non-nebulized fuel being thrown by 60 centrifugal effect to the inner walls of the housing 17 whereafter it flows downwardly to said passageway.

The blades 12—12 of blower 4 act to move the combustible mixture through pipe 61 to burner 65 60, thence to chamber 128 therein, through screen 127 to chamber 129 wherein it is ignited by the electrical discharges between electrodes 67 and 74—74, the burning of said mixture being effected initially under vaporizing plate 68 for the heating thereof.

During the period the mixture is burning under the vaporizing plate 68, armature 86 continues its upward movement and thermostatic device 75 75 is also heated sufficiently to effect movement of circuit closer 82 to the right. During the final

upward movement of said armature, collars 130 and 131 will act to raise circuit closers 163 and 116. As closer 115 is raised energy to motor 3 will flow from contact lever 82 through wires 133, 118, and circuit closer 114, wire 119 to motor 3 and thence to negative energy, in this manner maintaining continued operation of said motor. If the burner had failed to ignite, the failure of circuit closer 82 to move to the right would have opened the circuit to the motor when closer 116 was raised. Said failure would also effect flow of energy from lever 82 through wires 107, 134, circuit closer 135 wire 136, alarm 137 and thence to negative energy through wire 138, in this manner calling attention to the abnormal condition of the burner.

Assuming that circuit closer 82 has moved to the right normally, the raising of closer 116 will act to open the circuit to transformer 111, and as the electrical discharges cease, the origin of the burning flame under vaporizing plate 68 will move outwardly to the annular opening formed by the flanges 156 and 157, thereafter continuing to burn at this point until the motor 3 is stopped.

It will be noted that simultaneously with the opening of the circuit to the transformer 111, the circuit to the heating unit 55 is likewise opened.

As armature 85 completes its upward movement, circuit closer 132 raises and includes a holding winding 158 in the windings of the solenoid 30 86, in this manner materially reducing the amount of energy required thereby during the holding periods thereof.

Referring to Fig. 5, the combustible mixture producing unit 2 is located in a building 152 35 remotely from the burner 60, the pipe 61 being conducted under ground therebetween, said building 152 having a control panel 153 containing the apparatus 84 controlled by the thermostat 101 in building 151 said building having a furnace 150 40 wherein said burner 60 is located.

Whereas the combustible mixture producing unit 2 has been shown as supplying a combustible mixture for a fuel burner said unit is equally well adapted to supply said combustible mixture to an 45 internal combustion motor of the high speed type.

The solenoid 86 may be controlled by a time interval device 155, more fully described in my copending application for Letters Patent filed February 14, 1931, Serial Number 515,761 (since issued as U. S. Patent 2,030,542 on Feb. 11, 1936), and under which conditions the thermostat 101 would be adjusted to function only in event of excess heating of the space 100.

This application forms a continuing application of my copending application Serial Number 80,000, filed, January 8th, 1926.

What I claim is:—

1. The method of producing fog combustible mixtures for supporting combustion which involves, simultaneously producing a current of air and producing a stream of non-readily volatile liquid fuel thereinto, the fuel stream being produced independently of the air current, mechanically beating the fuel in the stream until it is disintegrated into uniform size closely approximated liquid globules so small they become electro-statically suspended in the air of the air current and thereby form a fog combustible mixture, and utilizing the combustible mixture for supporting combustion.

2. The method of producing fog combustible mixtures for supporting combustion which involves, simultaneously producing a current of air

and producing a stream of non-readily volatile liquid fuel flowing therewith, the fuel stream being produced independently of the air current, mechanically beating the fuel in the stream until a substantial portion thereof is disintegrated into uniform size closely approximated liquid globules so small they become electro-statically suspended in the air current and form a fog combustible mixture, separating the fog combustible mixture and the liquid fuel in the stream not disintegrated sufficiently to form a combustible mixture, returning the latter fuel portion to the source and utilizing the fog combustible mixture to support combustion.

3. The method of producing combustible mixtures which involves, simultaneously establishing a current of combustion supporting gas and a flowing stream of non-readily volatile liquid fuel in juxtaposition, mechanically beating the stream sufficiently to reduce the fuel therein into minute closely approximated uniform size liquid particles and simultaneously produce a gas tension therebetween and the surrounding combustion supporting gas for forming a stable fog combustible mixture which will support combustion when ignited.

4. The method of producing combustible mixtures which involves, simultaneously establishing a current of air and a flowing stream of non-readily volatile liquid fuel in juxtaposition, mechanically beating the stream sufficiently to reduce the fuel therein into the minutest divisible liquid particles before gasification thereof and simultaneously producing a gas tension therebetween and the surrounding air from forming a stable fog combustible mixture which will produce spontaneous combustion when ignited.

5. The method of producing combustible mixtures which involves, simultaneously establishing a current of air and a flowing stream of non-readily volatile liquid fuel in juxtaposition from separate sources, mechanically beating the stream sufficiently to reduce a substantial portion thereof into the minutest divisible liquid particles before gasification thereof and simultaneously producing a gas tension therebetween and the surrounding air for forming a stable spontaneous combustible mixture, separating the combustible mixture from the portion of the fuel stream not reduced to the minute particle state, and collecting and returning the latter named portion to the fuel source.

OSCAR A. ROSS.
